UNITED STATES PATENT OFFICE.

FRANK BENTLEY, OF NILES, OHIO.

BRICK-PALLET.

No. 838,665.

Specification of Letters Patent.

Patented Oct. 16, 1906.

Application filed January 27, 1906. Serial No. 298,184.

To all whom it may concern:

Be it known that I, FRANK BENTLEY, of Niles, in the county of Trumbull and State of Ohio, have invented certain new and useful 5 Improvements in Brick-Pallets; and I do hereby declare the following to be a full, clear, and exact description of the invention, such as will enable others skilled in the art to which it appertains to make and use the same.

The primary object of this invention is to provide a brick-pallet which will lessen the liability of damage to the bricks in placing and removing the trays on or from rack drier-cars or other rests upon which the brick-pallets may be located.

A further object is to provide an even bearing-surface, so as to prevent any strain upon the pallet which might tend to affect its surface or destroy the levelness thereof or cause the bricks to crack.

The invention will be hereinafter fully set forth, and pointed out in the claims.

In the accompanying drawings, Figure 1 is 25 a view in perspective of my preferred form of pallet. Fig. 2 shows a slight modification of the form of pallet shown in Fig. 1.

Referring to the drawings, 1 designates the pallet, which is composed of sheet metal, 30 which by reason of the fact that an even bearing-surface is obtained at both sides and both ends of the pallet may be made of much lighter material than heretofore.

According to the form shown in Fig. 1, the 35 edges of the sides 2 and ends 3 of the pallet are rolled downwardly and inwardly to strengthen the pallet and prevent it from getting out of shape and at the same time permit of the easy handling thereof without danger of injury to the hands of the operator. It 40 will be noted that according to the form shown in Fig. 1 the ends of the rolled edges

of the sides 2 are carried out to the plane of the rolled edges of the ends 3, so as to provide an even surface and prevent any angles or 45 shoulders which could catch on any angle or projection of a rack. Of course the ends of the sides 2 stop short of the planes of the ends 3, as shown in Fig. 2. In this arrangement the ends 3 are extended out to the planes of 50 the edges of the sides 2.

The advantages of my invention will be apparent. It will be seen that a pallet constructed in accordance therewith will retain an even level surface, will not be liable to 55 hurt the hands of an operator, and the chances of injuring the bricks by the pallets engaging with angles or projections of the trays is entirely overcome. It will also be seen that a solid support is had for the pallet 60 the full length and width thereof, thereby adding greatly to the strength and durability of the pallet and lessening liability of damage to the bricks located thereon.

I claim as my invention—

1. A brick-pallet having both of its sides and both ends correspondingly bent downwardly, the ends of one set of the downwardly-bent portions being extended to the 65 plane of the other set of downwardly-bent 70 portions.

2. A brick-pallet having both of its sides and both ends rolled downwardly to form corresponding bearing-surfaces for the pallet, the ends of one set of downwardly-rolled portions being extended to the plane of the other 75 set of downwardly-rolled portions.

In testimony whereof I have signed this specification in the presence of two subscribing witnesses.

FRANK BENTLEY.
